UNITED STATES PATENT OFFICE.

CHARLES A. TATUM, OF NEW YORK, N. Y., ASSIGNOR TO WHITALL TATUM COMPANY, OF NEW YORK, N. Y., A CORPORATION OF NEW JERSEY.

NIPPLE FOR NURSING-BOTTLES.

SPECIFICATION forming part of Letters Patent No. 712,157, dated October 28, 1902.

Application filed April 5, 1902, Serial No. 101,464. (No model.)

To all whom it may concern:

Be it known that I, CHARLES A. TATUM, a citizen of the United States, residing in the borough of Manhattan, city, county, and 5 State of New York, have invented a certain new and useful Improvement in Nipples for Nursing-Bottles, of which the following is a specification.

My invention relates to nipples for nursing-bottles, and has for its object to provide a nipple of this class which will be readily cleaned and which will not afford any spaces difficult of access in which injurious matter may lodge.

15 To this end my invention consists in the particular construction hereinafter described and claimed.

Reference is to be had to the accompanying drawings, in which—

20 Figure 1 is an elevation of my improved nipple. Fig. 2 is a sectional elevation thereof on line 2 2 of Fig. 3, and Fig. 3 is a plan.

The improved nipple comprises an approximately cylindrical lower section A, provided 25 with a reinforced edge or bead A' at the bottom and with a slanting shoulder portion A² at the top. This lower portion is adapted to engage the neck and mouth of the nursing-bottle, the shoulder resting on the edge of 30 the bottle.

The upper portion of the nipple is frusto-conical, as shown at A³, and terminates in a slightly-curved top A⁴, in which the central aperture A⁵ may be made. It is of course 35 immaterial whether a central aperture or a series of apertures be provided.

The nipple may be made of soft rubber, as usual.

When this nipple is placed on a bottle, it 40 will only be stretched laterally below the

shoulder A², but not above it, thus giving it a firm grip on the bottle.

On account of its being of reduced diameter at the top the nipple is readily cleaned, since all the interior surfaces are readily accessible 45 from the bottom, and there are no outwardly-bulging portions between the bottom and the top of the nipple to form interior recesses in which injurious matter may lodge. The nipple will therefore be easy to preserve in a 50 serviceable condition, and there will be no danger of affecting the health of the infant by the injurious influence of foreign matter left in the nipple owing to imperfect or difficult cleaning.

What I claim as new, and desire to secure by Letters Patent, is—

An elastic nipple for nursing-bottles, comprising an upper portion having a straight conical wall, the narrow portion of which is 60 at the discharge end of the nipple, a shoulder or enlargement located at the wide end of said conical upper portion and adapted to become seated upon the mouth of the nursing-bottle, and a substantially cylindrical lower 65 portion, the interior diameter of which is substantially equal to the greatest inner diameter of said enlargement, said lower portion being adapted to embrace the neck of the bottle adjacent to the mouth thereof, and being provided at its free edge with a thickened portion so as to give it a firm hold on the bottle at said free edge.

In testimony whereof I have signed my name to this specification in the presence of 75 two subscribing witnesses.

CHARLES A. TATUM.
